(57) **ABSTRACT**

A switching apparatus comprising a point detector connecting rod connected at one end to a switch machine and to at least one point at the opposite end. The point detector connecting rod is attached to the point via an angled block that permits a sliding motion relative to the point.

APPLICATIONS

This application claims the benefit under 35 U.S.C. § 120 of U.S. application Ser. No. 16/418,762, filed May 21, 2019, which claims the benefit under 35 U.S.C. § 119 of Provisional Application Ser. No. 62/674,523, filed May 21, 2018, each of which is incorporated herein by reference.

STATEMENT REGARDING FEDERALLY
SPONSORED RESEARCH

Not applicable.

BACKGROUND OF THE INVENTION

The invention relates to a railroad switch. More specifically, the invention relates to a point slider that accounts for thermal expansion and contraction of rails and points in a railroad switch, allowing proper operation of an indicator.

Points are movable section of rail used to direct a rail car along one of two lines at a junction. For example, a set of points could be used at a junction between a mainline and a branch line that diverges from the mainline. To show which track has been selected and to provide confirmation that complete switching of the points has occurred, an indicator rod is connected at one end to the set of points and to a switch machine or detector at the opposite end. In this configuration, the indicator rod mirrors the movement of the points. These components are used as a point indicator, which is a critical component because if the points are not fully switched, derailment of the train can occur.

Indicator rods are typically connected to the points at a right angle relative to the length of the track and extend beyond the rails to a switch machine, or detector, adjacent to the track. However, the points and other section of rail can expand and contract due to fluctuations in temperature. Any increase in length of the point will cause the angle of connection between the point and indicator rod to deviate from roughly 90 degrees, since the switch machine is in a fixed location and cannot move with the expanding points.

Others have attempted to mitigate the potential misalignment caused by thermal expansion by providing a sliding mechanism at the connection between the point and the indicator rod. However, these attempts have failed to account for the change in the distance between the switch machine and the point as the indicator rod slides along the connection to the point or angled stock rail. That is, a change in length of the distance between the switch machine and point occurs because the point or angled stock rail are tapered and moving along the length of this taper causes the indicator rod to be wedged towards or away from the detector. The length of the indicator rod—or more specifically, the horizontal displacement of the indicator rod along a line perpendicular to the rail—is used to indicate complete switching of the point. As such, a change in length of the indicator rod not related to a horizontal movement of the set of points can become problematic. Therefore, it would be advantageous to develop a point indicator that accounts for thermal expansion while maintaining sensitivity to horizontal displacement.

2
BRIEF SUMMARY

According to embodiments of the present invention a point indicator mechanism comprising an angled slider at a connection between the point and the indicator rods.

BRIEF SUMMARY OF THE SEVERAL VIEWS
OF THE DRAWINGS

FIG. 1 shows the angled slider according to one embodiment.

FIG. 2 is an alternative view of the angled point slider.

DETAILED DESCRIPTION

FIG. 1 shows a railroad switching apparatus 100 according to one embodiment. As shown in FIG. 1, the switching apparatus 100 comprises a stock rail 110, an angled stock rail 111, a left-hand point 112, a right-hand point 113, a front rod 120, a lockrod connecting rod 121, a point detector connecting rod 122, a switch machine 123, a switch rod 130, a set of rollers 131, and a pair of interconnecting blocks 132, 133. The front rod 120 is connected to the lockrod connecting rod 121, which can be moved in a direction roughly perpendicular to the stock rail 110 by the switch machine 123 to move both the left-hand point 112 and the right-hand point 113. As the points 112, 113 move, the point detector connecting rod 122, which is also connected to the points 112, 113, moves in a similar manner.

Detection of the movement of the point detector connecting rod 122 in the switch machine 123 can be used to indicate the position of the points 112, 113 and whether complete movement of the points 112, 113 has occurred. For example, during a switching movement, a rock from the ballast under the rail ties can be lodged between one of the points 112, 113 and one of the stock rails 110, 111, preventing the points 112, 113 from sitting flush against the stock rails 110, 111. If the gap is sufficiently large, a railcar risks derailing as it passes through the switch 100. The point detector connecting rod 122 is used to help identify such a condition before the railcar passes through the switch 100.

In certain situations, thermal expansion of the points 112, 113 can cause misalignment of the point detector connecting rod 122. For example, as the points 112, 113 move in a direction parallel to the stock rails 110, 111 due to thermal expansion or from the flange of train wheels pushing the points 112, 113, one of the points 112, 113 will slide along the stock rail 110 or angled stock rail 111. In the embodiment shown in FIG. 2, the right-hand point 113 is sliding on the angled stock rail 111. As the point 113 moves along the angled stock rail 111, it experiences a displacement towards the stock rail 110 (i.e. towards the center of the track) caused by the angle or taper of the tapered stock rail 111.

In a typical switching apparatus, the switch rod, front rod, point detector connecting rod and lock rod connecting rod would be bolted directly to the points themselves; as a result, in a typical switch apparatus, when the point experiences movement in a direction parallel to the stock rail, the switch rod, front rod, point detector connecting rod and lock rod connecting rod would move wherever the point moves. This typical movement could have two negative effects on the point detector connecting rod and lock rod connecting rod. First, the rods could lose their intended angular alignment in relation to the switch machine causing a loss of “indication”; and second, the rods could displace horizontally in relation to the switch machine causing a loss of “indication”.

FIG. 1 shows the switch 100 with the points 112, 113 in a first position. FIG. 2 shows the switch 100 with the point 113 extended along stock rail 111 due to thermal expansion, for example. As shown in FIGS. 1-2, the reverse angled point slider of the present invention eliminates both negative effects by allowing the points 112, 113 to move in a direction parallel to the stock rails 110, 111 while holding the switch rod 130, front rod 120, point detector connecting rod 122, and lock rod connecting rod 121 from moving in relation to the switch machine 123 by use of guide rollers 131, female dovetail blocks 132, and male dovetail blocks 133. The term 'dovetail' is used to describe a female slot that captures a male rail, where the male rail is adapted to slide back and forth within the female slot. While dovetail blocks 132, 133 are depicted in this example embodiment, block of varying shape that allow one block to slide within the other can be used.

Referring again to FIGS. 1-2, the female dovetail block 132 is bolted to each point 112, 113 and is cut or manufactured so that the sliding surface is parallel to the stock rail 110, 111 while the point is closed. The male dovetail block 133 is inserted inside the female dovetail 132 and allowed to slide freely. The switch rod 130 and front rod 120 are both bolted to the male dovetail block 132. The switch rod 130 is then prevented from moving in a direction along the stock rails 110, 111 by way of guide roller assemblies 131. The guide rollers 131 allow the switch rod 130 to be pushed side to side by the switch machine 123. Since the switch rod 130 and the front rod 120 are both bolted to the male dovetail blocks 133, the front rod 120, point detector connecting rod 122, and lock rod connecting rods 121 are prevented from moving in a direction along the stock rails 110, 111. Preventing this movement counteracts misalignment in relation to the switch machine 123. The reverse angle of the female dovetail block counteracts the left or right movement of the switch rod 130, front rod 120, point detector connecting rod 122, and lock rod connecting rod 121, thereby preventing horizontal displacement.

While the disclosure has been described in detail and with reference to specific embodiments thereof, it will be apparent to one skilled in the art that various changes and modification can be made therein without departing from the spirit and scope of the embodiments. Thus, it is intended that the present disclosure cover the modifications and variations of this disclosure provided they come within the scope of the appended claims and their equivalents.

What is claimed is:

1. A switching apparatus including a point indicator comprising:
  - a pair of stock rails comprising a first rail and a second rail;
  - a pair movable points comprising a first point and a second point;
  - a switch rod for moving the pair of movable points between an open position and a closed position, wherein a surface of the first point contacts the first rail in the closed position and a surface of the second point contacts the second rail in the open position; an indicator rod connected to the first point at a first sliding interface and to the second point at a second sliding interface, wherein the first sliding interface is parallel to the surface of the first point, and wherein the second sliding interface is parallel to the surface of the second point;
  - a first block disposed between the first sliding surface and the first point; and

4
a second block disposed between the second sliding surface and the second point, wherein the first block and the second block each has non-parallel sides.

2. The switching apparatus of claim 1, wherein at least one of the first block and the second block comprises:
  - a female dovetail block, and
  - a male dovetail block adapted to slidably engage the female dovetail block.
3. The switching apparatus of claim 1, wherein the second rail is non-parallel to the first rail.
4. The switching apparatus of claim 1, further comprising:
  - a switch machine connected to the indicator rod, operably connecting the switch machine to the first point and the second point.
5. The switching apparatus of claim 1, further comprising:
  - a guide roller attached to the indicator rod preventing movement of the indicator rod in a direction parallel to a longitudinal direction of the pair of stock rails.
6. A switching apparatus comprising:
  - a pair of stock rails comprising a first rail and a second rail;
  - a pair movable points comprising a first point and a second point;
  - a switch rod for moving the pair of movable points between an open position and a closed position, wherein a surface of the first point contacts the first rail in the closed position and a surface of the second point contacts the second rail in the open position; an indicator rod connected to the first point at a first sliding interface and to the second point at a second sliding surface, wherein the first sliding interface is non-parallel to an inner surface of the first point, wherein the second sliding interface is non-parallel to an inner surface of the second point;
  - a first block disposed between the first sliding surface and the first point; and
  - a second block disposed between the second sliding surface and the second point, wherein the first block and the second block each has non-parallel sides.
7. The switching apparatus of claim 6, wherein the second rail is non-parallel to the first rail.
8. The switching apparatus of claim 6, wherein an angle formed by the non-parallel sides of the first block equals an angle formed by an inner surface and an outer surface of the first point.
9. The switching apparatus of claim 6, wherein an angle formed by the non-parallel sides of the second block equals an angle formed by an inner surface and an outer surface of the second point.
10. The switching apparatus of claim 6, further comprising:
  - a switch machine connected to the pair of movable points via the indicator rod.
11. The switching apparatus of claim 6, further comprising:
  - a guide roller attached to the indicator rod preventing movement of the indicator rod in a direction parallel to a longitudinal direction of the pair of stock rails.
12. A switching apparatus comprising:
  - a pair of stock rails comprising a first rail and a second rail;
  - a pair movable points comprising a first point and a second point;
  - a switch rod for moving the pair of movable points between an open position and a closed position,

wherein a surface of the first point contacts the first rail in the closed position and a surface of the second point contacts the second rail in the open position; an indicator rod connected to the first point at a first sliding interface and to the second point at a second sliding surface,
wherein the first sliding interface is non-parallel to the second sliding interface.
